An image forming system includes an image forming apparatus that includes process units for different colors and a lifetime management device that manages lifetime information on each unit of the image forming apparatus. The lifetime management device counts the number of prints produced by the image forming apparatus with respect to each of photoconductor units and developing units in the process units, and measures an operation amount unique to the respective units. Based on the number of prints, service life of each unit and operation amount, the lifetime management device calculates the remaining lifetime of each unit.

LIFETIME MANAGEMENT DEVICE AND
IMAGE FORMING SYSTEMCROSS-REFERENCE TO RELATED
APPLICATIONS

The present document incorporates by reference the entire contents of Japanese priority document, 2005-346309 filed in Japan on Nov. 30, 2005.

BACKGROUND OF THE INVENTION

1. Field of the Invention

The present invention relates to an image forming system that includes an image forming apparatus mounted with a plurality of components and a lifetime management device that manages information on the lifetime of the components.

2. Description of the Related Art

When a failure occurs in a part of an image forming apparatus such as a copier, a facsimile machine, and a printer, depending on the type of the part, the image forming apparatus cannot be used until the part is replaced by a new one, and this imposes inconvenience on a user.

Therefore, various types of image forming systems have been proposed, which estimate the end of the service life of respective parts or components of an image forming apparatus to issue a request to replace a part which reaches its service life. For example, Japanese Patent Application Laid-open No. H9-146423 discloses such an image forming system. In the conventional image forming system, the number of prints produced by an image forming apparatus is calculated with respect to each of parts mounted thereon. When the number of prints exceeds a predetermined threshold for one of the parts, it is determined that the part has deteriorated to about the end of its service life due to printing operation. Then, a signal is transmitted to a remote monitoring device to request replacement of the part. In response to the request, a replacement worker, such as a service person, replaces the part before a failure occurs, which reduces the downtime of the image forming apparatus.

Some of the various parts mounted on the image forming apparatus deteriorate depending on an operation amount specific to the parts rather than the number of prints. For example, a developing roller, which does not closely contact recording paper during the printing operation, deteriorates depending on the operation amount including the total rotation time and the total rotation distance rather than the number of prints (hereinafter, this type of part is referred to as "operation amount-dependent deteriorated part"). On the other hand, a cleaning member that removes paper dust from the recording paper and toner remaining on an intermediate transfer belt, and a fixing roller that strongly contacts the recording paper deteriorates depending on the number of prints rather than the operation amount (hereinafter, this type of part is referred to as "print volume-dependent deteriorated part"). If the number of prints is completely proportional to the operation amount, the end of service life of each part can be accurately estimated based on the number of prints. However, the number of prints and the operation amount do not show a proportional correlation.

A factor of this relates to an idle operation at the start and the end of a print job. Specifically, the printing operation of the image forming apparatus includes a single printing operation in which an image is formed only on one recording sheet, and a continuous printing operation in which images are continuously formed on a plurality of recording sheets. In either printing operation, an idle operation, in which a sheet is

2

not fed to respective parts, is performed when a job starts and ends. The idle operation is performed for the same time period in the single printing operation and the continuous printing operation. Accordingly, in the single printing operation, the percentage of the idle operation time in the total operation time is high compared to the continuous printing operation. Further, in the continuous printing operation, as the number of continuous prints decreases, the percentage of the idle operation time increases. Therefore, when a user frequently performs single printing and rarely performs continuous printing of relatively a few copies, the operation amount is considerably large, while the number of prints is relatively small. In such a case, if the service life is estimated based only on the number of prints, the operation amount-dependent deteriorated part may reach the end of its service life before the estimated one. On the contrary, when a user performs continuous printing of a large number of copies frequently and single printing relatively infrequently, the operation amount is considerably small, while the number of prints is relatively large. In such a case, if the service life is estimated based only on the number of prints, it is likely to be determined that the operation amount-dependent deteriorated part is almost at the end of its service life even if sufficient time remains until the end.

Therefore, the present inventors have studied to estimate service life based on the operation record of each part, instead of the number of prints, for the operation amount-dependent deteriorated parts. However, the number of prints more or less relates to the progress of deterioration even in the operation amount-dependent deteriorated parts according to the type of recording paper. Specifically, paper dust can adhere to the operation amount-dependent deteriorated parts such as the developing roller, which does not closely contact recording paper, via the intermediate transfer belt and a photosensitive drum, which closely contact recording paper. When a user mainly uses recording paper likely to generate paper dust, such as low-quality paper, the amount of adhering dust considerably increases. As a result, the number of prints relates relatively closely to the progress of deterioration even in the operation amount-dependent deteriorated parts. In such a case, if the service life of the operation amount-dependent deteriorated part is estimated based only on the operation record, estimation accuracy decreases.

SUMMARY OF THE INVENTION

It is an object of the present invention to at least partially solve the problems in the conventional technology.

According to an aspect of the present invention, a lifetime management device for an image forming apparatus that forms an image on a recording medium and includes a plurality of components, includes a counting unit that counts number of prints produced by the image forming apparatus with respect to each of the components, a measuring unit that measures an operation amount of at least part of the components with respect to each of the components, and a calculating unit that calculates a remaining lifetime of each of the components based on at least one of a lifetime index, the number of prints, and the operation amount.

According to another aspect of the present invention, an image forming system includes an image forming apparatus that forms an image on a recording medium and includes a plurality of components, and a lifetime management device that manages lifetime information on each of the components of the image forming apparatus. The lifetime management device includes a counting unit that counts number of prints produced by the image forming apparatus with respect to

each of the components, a measuring unit that measures an operation amount of at least part of the components with respect to each of the components, and a calculating unit that calculates a remaining lifetime of each of the components based on at least one of a lifetime index, the number of prints, and the operation amount.

The above and other objects, features, advantages and technical and industrial significance of this invention will be better understood by reading the following detailed description of presently preferred embodiments of the invention, when considered in connection with the accompanying drawings.

BRIEF DESCRIPTION OF THE DRAWINGS

FIG. 1 is a schematic of a printer in an image forming system according to a first embodiment of the present invention;

FIG. 2 is an enlarged view of a yellow (Y) process unit of the printer;

FIG. 3 is a perspective view of the process unit;

FIG. 4 is a perspective view of a developing unit in the process unit;

FIG. 5 is an enlarged view of a fixing unit of the printer;

FIG. 6 is a perspective view of a Y toner cartridge in the printer;

FIG. 7 is a perspective view of a cartridge connecting portion, which is a part of a toner supply unit of the printer;

FIG. 8 is a perspective view of a Y suction pump of four suction pumps in the toner supply unit;

FIG. 9 is a perspective view of the toner supply unit and a peripheral configuration thereof;

FIG. 10 is a perspective view of a drive transmission unit, which is a drive transmission system fixed in the printer;

FIG. 11 is an overhead plan view of the drive transmission unit;

FIG. 12 is a partial perspective view of one end of the Y process unit;

FIG. 13 is a perspective view of a Y photoconductor gear in the printer and a peripheral configuration thereof;

FIG. 14 is a block diagram of one part of an electric circuit in the printer;

FIG. 15 is one example of the image forming system;

FIG. 16 is a flowchart of a replacement request process performed by a controller in the printer;

FIG. 17 is a detailed flowchart of a print count correction process shown in FIG. 16;

FIG. 18 is a flowchart of relevant parts of a remaining lifetime informing process performed by the controller;

FIG. 19 is a flowchart of relevant parts of a replacement order process performed by a remote monitoring device of the image forming system;

FIG. 20 is an enlarged view of four photoconductor gears and a peripheral configuration thereof in a printer of an image forming system according to a modification of the first embodiment;

FIG. 21 is a flowchart of relevant parts of a replacement request process performed by a controller of a printer in an image forming system according to a second embodiment; and

FIG. 22 is a detailed flowchart of a remaining lifetime correction process shown in FIG. 21.

DETAILED DESCRIPTION OF THE PREFERRED EMBODIMENTS

Exemplary embodiments of the present invention are explained below with reference to the accompanying draw-

ings. In the embodiments, the present invention is applied to an image forming system that includes an electrophotographic printer (hereinafter, "printer").

A basic configuration of a printer as an image forming apparatus of an image forming system according to a first embodiment is explained first referring to FIG. 1. The printer includes four process units 1Y, 1C, 1M, and 1K that form toner images of yellow, magenta, cyan, and black (hereinafter, "Y, C, M, and K"). The process units 1Y, 1C, 1M, and 1K have the same configuration except that they use toner of different colors Y, C, M, and K to form an image. FIG. 2 is an enlarged view of the process unit 1Y for forming a Y toner image. The process unit 1Y includes a photoconductor unit 2Y and a developing unit 7Y. As shown in FIG. 3, the photoconductor unit 2Y and the developing unit 7Y are detachably mounted on the printer to be integrated into the process unit 1Y. When detached from the printer, as shown in FIG. 4, the developing unit 7Y can be attached to and detached from the photoconductor unit 2Y.

The photoconductor unit 2Y includes a photosensitive drum 3Y as a latent image carrier, a drum cleaning unit 4Y, a discharger (not shown), a charger 5Y.

FIG. 2 depicts the charger 5Y that uniformly charges a surface of the photosensitive drum 3Y rotated clockwise in FIG. 2 by a drive unit (not shown). The charger 5Y uniformly charges the photosensitive drum 3Y by moving a charging roller 6Y rotated counterclockwise in FIG. 2 close to the photosensitive drum 3Y, while a charging bias is being applied thereto by a power source (not shown). Instead of the charging roller 6Y, a charger can also be used in which a charging brush contacts the photosensitive drum 3Y. Further, a charger can also be used which uniformly charges the photosensitive drum 3Y in the same manner as a scorotron charger. The surface of the photosensitive drum 3Y uniformly-charged by the charger 5Y is exposed and scanned by a laser beam emitted from an optical writing unit, thereby carrying a Y electrostatic latent image.

The developing unit 7Y includes a first developer container 9Y including a first screw 8Y therein. The developing unit 7Y further includes a second developer container 14Y including a density sensor consisting of a permeability sensor (hereinafter, density sensor) 10Y, a second screw 11Y, a developing roller 12Y, and a doctor blade 13Y. The first and second developer containers contain a Y developer (not shown) including a magnetic carrier and a negatively charged Y toner. The first screw 8Y is rotated by the drive unit (not shown) to convey the Y developer in the first developer container 9Y from front to back in a direction perpendicular to the drawing. The Y developer passes through an opening (not shown) on a partition between the first and second developer containers 9Y and 14Y to enter the second developer container 14Y.

The second screw 11Y in the second developer container 14Y is rotated by the drive unit (not shown) to transport the Y developer from back to front in FIG. 2. The toner density of the Y developer being transported is detected by the density sensor 10Y fixed on the bottom of the second developer container 14Y. In FIG. 2, above the second screw 11Y that transports the Y developer is arranged the developing roller 12Y in parallel to the second screw 11Y. The developing roller 12Y includes a magnet roller 16Y in a developing sleeve 15Y formed of a non-magnetic pipe rotated counterclockwise in FIG. 2. A part of the Y developer transported by the second screw 11Y is drawn onto the surface of the developing sleeve 15Y by a magnetic force of the magnet roller 16Y. A film thickness thereof is regulated by the doctor blade 13Y arranged to hold a predetermined gap between the developing sleeve 15Y and the doctor blade 13Y. The Y developer

is then transported to a developing area opposite to the photosensitive drum **3Y**, so that the Y toner is adhered to the Y electrostatic latent image on the photosensitive drum **3Y**. The Y developer with the Y toner being consumed due to development is returned onto the second screw **11Y** with the rotation of the developing sleeve **15Y** of the developing roller **12Y**. When the Y developer is transported to the front side in FIG. 2, the Y developer is returned to the first developer container **9Y** via the opening (not shown).

A permeability detection result of the Y developer by the density sensor **10Y** is sent to a controller (not shown) as a voltage signal. The permeability of the Y developer correlates with the Y toner density of the Y developer, and the density sensor **10Y** outputs a voltage of a value corresponding to the Y toner density. The controller includes a random access memory (RAM), which stores $Y V_{tref}$, i.e., a target value of an output voltage from the density sensor **10Y**, and data of $C V_{tref}$, $M V_{tref}$, and $K V_{tref}$, i.e., target values of the output voltage from the C, M, and K density sensors mounted on other developing units **7C**, **7M**, and **7K**. The developing unit **7Y** compares a value of the output voltage from the density sensor **10Y** with the $Y V_{tref}$, and drives a Y toner supply unit for time corresponding to the comparison result. Due to this drive, an adequate amount of Y toner is supplied to the Y developer, in which the Y toner has been consumed due to development and the toner density has decreased, by the first developer container **9Y**. Accordingly, the Y toner density of the Y developer in the second developer container **14Y** is maintained in a predetermined range. The same toner supply control is performed with respect to the developer in the process units (**1C**, **1M**, **1K**) for other colors.

The Y toner image formed on the photosensitive drum **3Y** is intermediately transferred onto an intermediate transfer belt. The drum cleaning unit **4Y** in the photoconductor unit **2Y** removes remaining toner on the surface of the photosensitive drum **3Y**, having subjected to the intermediate transfer process. The surface of the photosensitive drum **3Y** having subjected to the cleaning process is discharged by the discharger (not shown). Due to the discharge, the surface of the photosensitive drum **3Y** is initialized and prepared for the next image formation. In FIG. 1, also in the process units **1C**, **1M**, and **1K** for other colors, the C, M, and K toner image is formed on the photosensitive drum **3C**, **3M**, and **3K**, respectively, in the same manner and intermediately transferred onto the intermediate transfer belt.

An optical write unit **20** is arranged below the process units **1Y**, **1C**, **1M**, and **1K** in FIG. 1. The optical write unit **20** as a latent image forming unit irradiates a laser beam **L** emitted based on the image information onto the photosensitive drums **3Y**, **3C**, **3M**, and **3K** of the respective process units **1Y**, **1C**, **1M**, and **1K**. Accordingly, Y, C, M, and K electrostatic latent images are formed respectively on the photosensitive drums **3Y**, **3C**, **3M**, and **3K**. The optical write unit **20** irradiates the laser beam **L** emitted from the light source via a plurality of optical lenses and mirrors, while deflecting the laser beam by a polygon mirror **21** rotated by a motor. Instead of this configuration, an optical write unit that performs optical scan by light-emitting diode (LED) arrays can be employed.

A first paper feed cassette **31** and a second paper feed cassette **32** are arranged below the optical write unit **20** to be overlapped on each other in a vertical direction. Recording paper **P** is stored in these paper feed cassettes in a state of paper stack in which plural sheets of the recording paper are piled, and a first paper feed roller **31a** and a second paper feed roller **32a** contact the top sheet of the recording paper **P**. When the first paper feed roller **31a** is rotated counterclockwise in

FIG. 1 by a drive unit (not shown), the top sheet of the recording paper **P** in the first paper feed cassette **31** is discharged toward a paper feed path **33** arranged to extend in the vertical direction on the right of the cassette in FIG. 1. Further, when the second paper feed roller **32a** is rotated counterclockwise in FIG. 1 by the drive unit (not shown), the top sheet of the recording paper **P** in the second paper feed cassette **32** is discharged toward the paper feed path **33**. In the paper feed path **33**, a plurality of carrier roller pairs **34** is arranged, so that the recording paper **P** fed to the paper feed path **33** is put between the rollers of the carrier roller pairs **34** and carried from the lower part to the upper part in FIG. 1 in the paper feed path **33**.

A resist roller pair **35** is arranged at the end of the paper feed path **33**. Upon insertion of the recording paper **P** fed from the carrier roller pair **34** between the rollers, the resist roller pair **35** temporarily stops the rotation of the rollers. The recording paper **P** is then fed to a secondary transfer nip (described later) at an appropriate timing.

Above the process units **1Y**, **1C**, **1M**, and **1K** is arranged a transfer unit **40** that endlessly moves an intermediate transfer belt **41** counterclockwise in FIG. 1, while extending the intermediate transfer belt **41**. The transfer unit **40** includes a belt cleaning unit **42**, a first bracket **43**, and a second bracket **44** in addition to the intermediate transfer belt **41**. The transfer unit **40** further includes four primary transfer rollers **45Y**, **45C**, **45M**, and **45K**, a secondary transfer backup roller **46**, a drive roller **47**, a supplementary roller **48**, and a tension roller **49**. The intermediate transfer belt **41** is endlessly moved counterclockwise in FIG. 1 due to rotation of the drive roller **47**, while being extended over eight rollers. The four primary transfer rollers **45Y**, **45C**, **45M**, and **45K** put the endlessly moved intermediate transfer belt **41** between the photosensitive drums **3Y**, **3C**, **3M**, and **3K** and the primary transfer rollers to form a primary transfer nip. The primary transfer rollers **45Y**, **45C**, **45M**, and **45K** then apply a transfer bias of a polarity (for example, positive) opposite to that of the toner to a back face (internal circumference of a loop) of the intermediate transfer belt **41**. While the intermediate transfer belt **41** sequentially passes the primary transfer nips for Y, C, M, and K with the endless movement, the Y, C, M, and K toner images on the photosensitive drums **3Y**, **3C**, **3M**, and **3K** are superposed and primarily transferred on a front face thereof. Accordingly, a four-color-superposed toner image (hereinafter, "four-color toner image") is formed on the intermediate transfer belt **41**.

The secondary transfer backup roller **46** puts the intermediate transfer belt **41** between a secondary transfer roller **50** arranged outside of the loop of the intermediate transfer belt **41** and the secondary transfer backup roller **46**, to form a secondary transfer nip. The resist roller pair **35** forwards the recording paper **P** put between the rollers toward the secondary transfer nip at a timing synchronized with the four-color toner image on the intermediate transfer belt **41**. The four-color toner image on the intermediate transfer belt **41** is secondarily batch-transferred onto the recording paper **P** in the secondary transfer nip, due to an influence of a secondary transfer field formed between the secondary transfer roller **50** and the secondary transfer backup roller **46**, to which a secondary transfer bias is applied, and a nip pressure. The four-color toner image becomes a full color toner image, coupled with white of the recording paper **P**.

Residual toner, which has not been transferred to the recording paper **P**, adheres on the intermediate transfer belt **41** after having passed through the secondary transfer nip. The residual toner is cleaned by the belt cleaning unit **42**. In the belt cleaning unit **42**, a cleaning blade **42a** contacts the front

face of the intermediate transfer belt 41, thereby scraping and removing the residual toner on the belt.

A fixing unit 60 is arranged above the secondary transfer nip in FIG. 1. As shown in FIG. 5, the fixing unit 60 includes a pressurizing heating roller 61 that contains a heat source 61a such as a halogen lamp, and a fixing belt unit 62. The fixing belt unit 62 includes a fixing belt 64, a heating roller 63 including a heat source 63a such as a halogen lamp, a tension roller 65, a drive roller 66, and a temperature sensor 67. The fixing belt unit 62 endlessly moves the endless fixing belt 64 counterclockwise in FIG. 5, while extending the fixing belt 64 across the heating roller 63, the tension roller 65, and the drive roller 66. In the process of endless movement, the fixing belt 64 is heated from a backside by the heating roller 63. The pressurizing heating roller 61 rotates clockwise in FIG. 5 contacts a position where the fixing belt 64 heated in this manner is spanned over the heating roller 63 from the front face side. Accordingly, a fixing nip is formed, where the pressurizing heating roller 61 and the fixing belt 64 contact each other.

The temperature sensor 67 is arranged to face the front face of the fixing belt 64 via a predetermined gap, outside of the loop of the fixing belt 64, and detects a surface temperature of the fixing belt 64 immediately before approaching the fixing nip. The detection result is transmitted to a fixing power source circuit (not shown). The fixing power source circuit controls on/off of power supply relative to the heat source 63a contained in the heating roller 63 and the heat source 61a contained in the pressurizing heating roller 61. Accordingly, the surface temperature of the fixing belt 64 is maintained at about 140 degrees.

In FIG. 1, the recording paper P having passed through the secondary transfer nip is separated from the intermediate transfer belt 41, and forwarded into the fixing unit 60. During a process of transport from the lower part to the upper part in FIG. 1, while being put between the fixing nip in the fixing unit 60, the recording paper P is heated and pressed by the fixing belt 64, thereby fixing the full color toner image.

The recording paper P having subjected to the fixing process in this manner passes through the rollers of a paper ejection roller pair 69 and ejected to the outside of the machine. A stack unit 68 is formed on the upper face of the housing of the printer, and the recording paper P ejected to the outside of the machine by the paper ejection roller pair 69 is sequentially stacked in the stack unit 68.

Four toner cartridges 100Y, 100C, 100M, and 100K for storing the Y, C, M, and K toners are arranged above the transfer unit 40. The Y, C, M, and K toners in the toner cartridges 100Y, 100C, 100M, and 100K are appropriately supplied to the developing units 7Y, 7C, 7M, and 7K in the process units 1Y, 1C, 1M, and 1K. These toner cartridges 100Y, 100C, 100M, and 100K can be attached to or detached from the printer, separately from the process units 1Y, 1C, 1M, and 1K.

FIG. 6 is a perspective view of the toner cartridge 100Y. The toner cartridge 100Y includes a bottle part 101Y for storing the Y toner (not shown), and a cylindrical holder part 102Y. The holder part 102Y rotatably holds the bottle part 101Y, while engaging with a point of the bottle part 101Y to cover an opening (not shown) formed at the point of the bottle part 101Y. On the bottle part 101Y, screw-shape protrusions 103Y protruding from outside toward inside are embossed along the internal circumference thereof. When the bottle part 101Y is driven by a drive system (not shown), the Y toner in the bottle part 101Y moves from the bottom side of the bottle toward the point side of the bottle along the screw-shape protrusions, and flows into the cylindrical holder part 102Y,

through the opening (not shown) provided at the point of the bottle part 101Y, which is a toner container.

A nozzle receiving port 109Y is formed at the end of the holder part 102Y in a bottle axial direction. The nozzle receiving port 109Y is for receiving a suction nozzle fixed on the printer side. Pin receiving ports 110Y having a slightly smaller diameter than that of the nozzle receiving port are formed on both sides of the nozzle receiving port 109Y in FIG. 6. The pin receiving ports 110Y are formed, respectively, at positions deviated from a rotation axis of the bottle part 101Y, and a pin insertion path (not shown) is formed in the inner side thereof to extend in a direction parallel to the rotation axis of the bottle part 101Y. As the bottle part 101Y, a resin material having a high rigidity so as not to be deformed by an impact at the time of rotation by a drive transmission gear is used.

FIG. 7 is a perspective view of a cartridge connecting portion 71Y, which is a part of a toner supply unit. The cartridge connecting portion 71Y is fixed at the upper end of a flow tube 72Y for allowing the Y toner to flow, so that a suction nozzle 73Y extends in a horizontal direction. At the end of the suction nozzle 73Y, a toner receiving port 74Y is formed to receive the Y toner. Bar-shaped positioning pins 75Y are fixed on both sides of the suction nozzle 73Y to extend in the horizontal direction (in a direction parallel to the rotation axis of the bottle part). The positioning pins 75Y, which are protrusions of the cartridge connecting portion 71Y as a positioning member, protrude over the end of the suction nozzle 73Y.

When the toner cartridge 100Y is to be set on a cartridge mounting base of the toner supply unit, at first, an opening/closing door (not shown) on a side of the printer is opened so that the cartridge mounting base in the toner supply unit is exposed. On the cartridge mounting base, four depressions in a semi-cylindrical shape are provided in parallel, for mounting four toner cartridges for Y, C, M, and K in parallel. An operator holds the toner cartridge 100Y with the holder part 102Y directed to the front. The operator then puts the holder part 102Y at the end of a depression for Y, of four semi-cylindrical depressions provided on the cartridge mounting base, and slides the cartridge along the rotation axis of the bottle part to insert the entire cartridge. The operator pushes the toner cartridge 100Y to a predetermined position by this sliding movement, and sets the toner cartridge 100Y on the cartridge mounting base.

The two positioning pins 75Y in the cartridge connecting portion 71Y in the toner supply unit are fixed such that the point thereof protrudes than the point of the suction nozzle 73Y. The point thereof is more tapered than the rear end. During the insertion of the toner cartridge in the cartridge mounting base at the time of setting the toner cartridge, the tapered points of the two positioning pins 75Y respectively enter into the two pin receiving ports 110Y of the toner cartridge 100Y shown in FIG. 6. When the toner cartridge 100Y is further inserted, the rear ends of the positioning pins 75Y thicker than the point thereof also enter into the pin receiving port 110Y, thereby positioning the toner cartridge 100Y in a direction orthogonal to the rotation axis on the cartridge mounting base.

After such positioning is performed, when the toner cartridge 100Y is further inserted, the suction nozzle 73Y in the cartridge connecting portion 71Y enters into the nozzle receiving port 109Y in the holder part 102Y. Setting of the toner cartridge 100Y is complete at a point in time when the suction nozzle 73Y is pushed into an insertion path (115Y) extending inside of the nozzle receiving port 109Y.

The thus set toner cartridge 100Y makes a gear portion 111Y formed at the point of the bottle part 110Y engage with the drive transmission gear (not shown) fixed in the toner supply unit. When the drive transmission gear is rotated, the bottle part 101Y rotates, while being held by the holder part 102Y. Due to this rotation, the Y toner in the bottle part 101Y is carried from the rear end toward the point of the bottle, and flows into the holder part 102Y.

The suction pump is connected to an area (not shown) of the flow tube 72Y connected to the suction nozzle 73Y, and air and the toner in the flow tube 72Y are sucked due to the operation thereof. The suction force is transmitted to the holder part 102Y through the flow tube 72Y and the suction nozzle 73Y. The Y toner in the holder part 102Y is then sucked into the suction nozzle 73Y, and supplied to the developing unit 7Y in the process unit 1Y.

While the toner cartridge 100Y for storing the Y toner has been explained in detail, the toner cartridges for other colors (100C, 100M, and 100K) have the same configuration.

FIG. 8 is a perspective view of a suction pump 78Y of four suction pumps in the toner supply unit. The suction pump 78Y is of a type referred to as uniaxial eccentric screw pump (generally called as monopump). A pump part 80Y is formed of a rotor 81Y machined in an eccentric double screw shape from a metal or a resin having high rigidity, a stator 82Y in which a double screw-shape cavity is formed in a material of rubber or the like, and a resin holder for containing these rotor and stator. The suction pump 78Y also includes a discharge part 83Y, and a motor 84Y for rotating the rotor 81Y, in addition to the pump part 80Y. When the double screw-shape rotor 81Y rotates in the stator 82Y, a negative pressure is generated on the suction side (the right side in FIG. 8) of the pump part 80Y. Due to the negative pressure, the Y toner in the toner cartridge 100Y is sucked via the flow tube 72Y and the like. The Y toner reaches the pump part 80Y of the suction pump 78Y, passes through the stator 82Y, and is discharged from the discharge part 83Y. Suction pumps for other colors have the same configuration.

FIG. 9 is a perspective view of a toner supply unit 70 and a peripheral configuration thereof. The toner supply unit 70 includes a cartridge mounting base 77, four cartridge connecting portions 71Y, 71C, 71M, and 71K, and four suction pumps 78Y, 78C, 78M, and 78K. The cartridge mounting base 77 includes four semi-cylindrical depressions for mounting the four toner cartridges 100Y, 100C, 100M, and 100K parallel with each other. The transfer unit (not shown) is arranged below the cartridge mounting base 77, and the four developing units are arranged further below. In FIG. 9, only the developing unit 7K is shown of the four developing units for simplicity.

On the side of the printer housing (not shown), the opening/closing door for replacing the cartridge is provided, and when this door is opened, the toner supply unit 70 in the housing is exposed on the inner side of FIG. 9. The operator pushes the toner cartridges 100Y, 100C, 100M, and 100K in a longitudinal direction of the bottle to slide the cartridges on the cartridge mounting base 77, thereby setting the cartridges in the toner supply unit 70.

A connecting unit support plate 79 for supporting the four cartridge connecting portions 71Y, 71C, 71M, and 71K is arranged in a standing condition at one end of the cartridge mounting base 77. The suction nozzles of the cartridge connecting portions 71Y, 71C, 71M, and 71K are respectively inserted into a nozzle insertion passage (not shown) in the toner cartridges 100Y, 100C, 100M, and 100K mounted on the cartridge mounting base 77. The suction pumps 78Y, 78C, 78M, and 78K are coupled to the end of flow tubes 72Y, 72C,

72M, and 72K of the cartridge connecting portions 71Y, 71C, 71M, and 71K. A toner supply port E of each developing unit is positioned immediately below the respective suction pumps 78Y, 78C, 78M, and 78K. The Y, C, M, and K toners respectively discharged from the discharge part of the suction pumps 78Y, 78C, 78M, and 78K are supplied to the inside of the developing unit via the toner supply port of the corresponding developing unit. In FIG. 9, while only the developing unit 7K is shown, the developing units 7Y, 7M, and 7C are respectively positioned immediately below the suction pumps 78Y, 78M, and 78C.

FIG. 10 is a perspective view of a drive transmission unit on the body side, which is a drive transmission system fixed in the printer. FIG. 11 is an overhead plan view of the drive transmission unit. The support plate is arranged in a standing condition in the printer housing, and four process drive motors 120Y, 120C, 120M, and 120K are fixed thereto. Drive gears 121Y, 121C, 121M, and 121K are respectively fixed to a rotation shaft of the process drive motors 120Y, 120C, 120M, and 120K. Developing gears 122Y, 122C, 122M, and 122K that can slide and rotate, while engaging with a fixed shaft (not shown) provided in a protruding condition on the support plate, are arranged below the rotation shafts of the process drive motors 120Y, 120C, 120M, and 120K. The developing gears 122Y, 122C, 122M, and 122K respectively include first gears 123Y, 123C, 123M and 123K and second gears 124Y, 124C, 124M and 124K, which rotate on the same rotation shaft. The second gears 124Y, 124C, 124M, and 124K are positioned on the point side of the rotation shaft of the process drive motors 120Y, 120C, 120M, and 120K than the first gears 123Y, 123C, 123M, and 123K. The developing gears 122Y, 122C, 122M, and 122K slide and rotate on the fixed shaft due to the rotation of the process drive motors 120Y, 120C, 120M, and 120K, while engaging the first gears 123Y, 123C, 123M, and 123K with the drive gears 121Y, 121C, 121M, and 121K of the process drive motors 120Y, 120C, 120M, and 120K.

On the left side of the developing gears 122Y, 122C, 122M, and 122K, first relay gears 125Y, 125C, 125M, and 125K that slide and rotate while engaging with the fixed shaft (not shown) are arranged. These relay gears respectively engage with the second gears 124Y, 124C, 124M, and 124K of the developing gears 122Y, 122C, 122M, and 122K, and slide and rotate on the fixed shaft due to a rotation driving force from the developing gears 122Y, 122C, 122M, and 122K. The first relay gears 125Y, 125C, 125M, and 125K not only engage with the second gears 124Y, 124C, 124M, and 124K on an upstream side of a drive transmission direction, but also engage with clutch input gears 126Y, 126C, 126M, and 126K on a downstream side of the drive transmission direction. These clutch input gears 126Y, 126C, 126M, and 126K are respectively supported by developing clutches 127Y, 127C, 127M, and 127K. The developing clutches 127Y, 127C, 127M, and 127K transmit the rotation driving force to respective clutch shafts of the clutch input gears 126Y, 126C, 126M, and 126K, or make the clutch input gears 126Y, 126C, 126M, and 126K run idle, with on/off control of power supply by the controller (not shown). Clutch output gears 128Y, 128C, 128M, and 128K are respectively fixed on the point side of the clutch shafts of the developing clutches 127Y, 127C, 127M, and 127K. When the power is supplied to the developing clutches 127Y, 127C, 127M, and 127K, the rotation driving force of the clutch input gears 126Y, 126C, 126M, and 126K is transmitted to the clutch shafts, to rotate the clutch output gears 128Y, 128C, 128M, and 128K, respectively. On the other hand, when the power supply to the developing clutches 127Y, 127C, 127M, and 127K is cut off, even if the process

11

drive motors 120Y, 120C, 120M, and 120K are rotating, since the clutch input gears 126Y, 126C, 126M, and 126K run idle on the clutch shafts, the rotation of the clutch output gears 128Y, 128C, 128M, and 128K stops.

Referring to FIG. 11, on the left side of the clutch output gears 128Y, 128C, 128M, and 128K, second relay gears 129Y, 129C, 129M, and 129K that can slide and rotate while engaging with the fixed shaft (not shown) are arranged, and rotate while engaging with the clutch output gears 128Y, 128C, 128M, and 128K.

On the printer, the following drive transmission system is configured to correspond to the four process units. That is, the drive transmission system includes the process drive motor 120, the drive gear 121, the first gear 123 and the second gear 124 of the developing gear 122, the first relay gear 125, the clutch input gear 126, the clutch output gear 128, and the second relay gear 129, and the driving rotation force is transmitted in this order.

FIG. 12 is a partial perspective view of one end of the process unit 1Y. A shaft member of the developing sleeve 15Y in a casing of the developing unit 7Y penetrates the side of the casing and protrudes to the outside. A sleeve upstream gear 131Y is fixed to the protruding shaft member. A fixed shaft 132Y is provided in a protruding condition on the side of the casing, and a third relay gear 130Y engages with the sleeve upstream gear 131Y, while engaging slidably and rotatably with the fixed shaft 132Y.

In a state that the process unit 1Y is set on the printer, the second relay gear 129Y shown in FIGS. 10 and 11 engages with the third relay gear 130Y, in addition to the sleeve upstream gear 131Y. The rotation driving force of the second relay gear 129Y is sequentially transmitted to the third relay gear 130Y and the sleeve upstream gear 131Y, thereby rotate the developing sleeve 15Y.

While only the process unit 1Y has been explained with reference to the drawings, also in the process units for other colors, the rotation driving force is transmitted to the developing sleeve as the developing member in the same manner.

In FIG. 12, while only the one end of the process unit 1Y is shown, the shaft member at the other end of the developing sleeve 15Y penetrates the side of the casing at the other end and protrudes to the outside, and a sleeve downstream gear (not shown) is fixed to the protruding portion. The first screw 8Y and the second screw 11Y shown in FIG. 2 also allow the shaft member thereof to penetrate the side of the casing at the other end, and a first screw gear and a second screw gear (not shown) are fixed to the protruding portion. When the developing sleeve 15Y rotates due to transmission of driving force of the sleeve upstream gear 131Y, the sleeve downstream gear rotates at the other end. Accompanying this rotation, the second screw 11Y that receives the driving force with the second screw gear engaging with the sleeve downstream gear rotates, and the first screw 8Y that receives the driving force with the first screw gear engaging with the second screw gear also rotates. The process units for other colors have the same configuration.

Thus, the developing gear groups consisting of the drive gear 121, the developing gear 122, the first relay gear 125, the clutch input gear 126, the clutch output gear 128, the second relay gear 129, the third relay gear 130, the sleeve upstream gear 131, the sleeve downstream gear, the second screw gear, and the first screw gear is formed in four sets, corresponding to the process units.

FIG. 13 is a perspective view of a photoconductor gear 133Y and a peripheral configuration thereof. The drive gear 121Y engages with the photoconductor gear 133Y as a latent image gear, in addition to the first gear 123Y of the develop-

12

ing gear 122Y. The photoconductor gear 133Y is fixed to a rotation shaft in a Y photosensitive drum (not shown), to form a part of the Y process unit. A diameter of the photoconductor gear 133Y is larger than that of the photosensitive drum.

5 When the process drive motor 120Y rotates, the rotation driving force thereof is transmitted from the drive gear 121Y to the photoconductor gear by single-reduction gearing, thereby rotating the photosensitive drum. The process units for other colors have the same configuration. Thus, the printer 10 in the image forming system includes four gear groups, each consisting of the drive gear 121 and the photoconductor gear 133, corresponding to the process units.

In FIG. 1, the first bracket 43 in the transfer unit 40 swings at a predetermined angle of rotation, centering on the rotation axis of the supplementary roller 48, with drive on/off of a solenoid (not shown). When forming a monochrome image, the printer of the image forming system slightly rotates the first bracket 43 counterclockwise in FIG. 1 by driving the solenoid. Due to this rotation, the primary transfer rollers 45Y, 45C, and 45M revolve counterclockwise, so that the intermediate transfer belt 41 is separated from the photosensitive drums 3Y, 3C, and 3M. Only the process unit 1K of the four process units 1Y, 1C, 1M, and 1K is driven to form a monochrome image. Accordingly, at the time of forming the monochrome image, wear of the process units due to useless driving of the process units 1Y, 1C, and 1M can be prevented.

20 In each color, the developing gear can be driven by a developing motor different from that of the photoconductor gear. In this case, a driven distance D of the developing unit 30 (i=5 to 8) can be calculated based on the driving time of the developing motor.

FIG. 14 is a block diagram of a part of an electric circuit in the printer of the image forming system. In FIG. 14, a controller 200 includes a central processing unit (CPU) 200a as a 35 calculation unit, a RAM 200b, and a read only memory (ROM) 200c, and controls the entire printer. A control program for controlling respective units in the printer is stored in the RAM 200b or the ROM 200c, and based on the control 40 program, the units are controlled and various characteristics are ascertained based on an output signal from respective sensors. The process drive motors 120Y, 120C, 120M, and 120K and the developing clutches 127Y, 127C, 127M, and 127K are connected to the controller 200 having such a configuration via an input/output (I/O) interface 201. Further, 45 process unit sensors 202Y, 202C, 202M, and 202K, a transfer unit sensor 203, a secondary transfer-unit sensor 204, a print counter 205, an operation display unit 206, a modem 207, a transfer belt motor 208, a secondary transfer motor 209, a fixing motor 210, and a fixing unit sensor 211 are also connected to the controller 200.

The process unit sensors 202Y, 202C, 202M, and 202K detect the process units 1Y, 1C, 1M, and 1K set in the printer, respectively, and output a detection signal to the controller 200.

55 The transfer unit sensor 203 detects the transfer unit 40 set in the printer and outputs a detection signal to the controller 200.

The secondary transfer-unit sensor 204 detects the secondary transfer unit formed of the secondary transfer roller 50 and the like set in the printer and outputs a detection signal to the controller 200.

The fixing unit sensor 211 detects the fixing unit 60 set in the printer and outputs a detection signal to the controller 200. The print counter 205 counts the accumulated number of prints by the printer immediately after shipment from factory. The print counter 205 counts up the number of prints every time the printing operation is performed relative to one sheet

of recording paper, and outputs a count-up signal to the controller 200. Further, the print counter 205 outputs a signal indicating the accumulated number of prints to the controller 200 in response to a request from the controller 200.

The operation display unit 206 includes a plurality of key switches and a touch panel (not shown), to convert an input operation relative to the key switches and the touch panel by the operator to an input signal, and output the input signal to the controller 200. Further, the operation display unit 206 displays an image based on a control signal from the controller 200 on the touch panel.

The modem 207 transmits a signal transmitted from the controller 200 to a remote apparatus via a telephone line (not shown).

The transfer belt motor 208 is a rotation driving source of the drive roller 47 in the transfer unit 40, and endlessly moves the intermediate transfer belt 41 with the rotation thereof.

The secondary transfer motor 209 is a rotation driving source of the secondary transfer roller 50 that contacts the front face of the intermediate transfer belt 41 to form the secondary transfer nip. The fixing motor 210 is a rotation driving source of the rollers and the fixing belt in the fixing unit 60.

The controller 200 detects detachment of the process units 1Y, 1C, 1M, and 1K relative to the printer, based on a combination of fall (OFF) and rise (ON) of the output signal from the process unit sensors 202Y, 202C, 202M, and 202K. The controller 200 detects detachment of the transfer unit 40 relative to the printer, based on the combination of fall and rise of the output signal from the transfer unit sensor 203. The controller 200 further detects detachment of the secondary transfer roller 50 relative to the printer, based on the combination of fall and rise of the output signal from the secondary transfer-unit sensor 204. Further, the controller 200 detects detachment of the fixing unit 60 relative to the printer, based on the combination of fall and rise of the output signal from the fixing unit sensor 211.

In the printer having the above basic configuration, an image forming unit that forms an image on the recording paper P as the recording member is configured by a combination of the process units 1Y, 1C, 1M, and 1K, the transfer unit 40, the belt cleaning unit 42, the secondary transfer unit include the secondary transfer roller 50, and the fixing unit 60.

The characteristic configuration of the image forming system is explained next.

FIG. 15 is one example of the image forming system. The image forming system includes at least one printer installed in the user's site and a lifetime management device (not shown). In FIG. 15, an example of the image forming system including 16 printers A to P (501 to 516) installed in geographical environments different from each other is shown. In practice, the image forming system often includes several hundreds to several thousands printers. The 16 printers A to P (501 to 516) of respective users are connected to a remote monitoring device 600 in a maintenance service center via the telephone line. The lifetime management device is provided in the printer.

In the maintenance service center, technicians highly skilled in failure diagnosis, inspection, and repair of the printer are at work, and the technician is dispatched to the user according to a request from each user. The printers A to P (501 to 516) include a function referred to as emergency call, and can transmit an emergency call signal including information of a failure content to the remote monitoring device 600 in the maintenance service center via the telephone line. The main-

tenance service center immediately dispatches the technician upon receiving the emergency call signal by the remote monitoring device 600.

The remote monitoring device 600 in the maintenance service center is connected to an order acceptance terminal 610 of a parts center. In the parts center, various parts of the printers are stocked, and replacement operators who can perform replacement work of these parts are assigned. The order acceptance terminal 610 in the parts center dispatches the replacement operator to the user together with the parts based on a replacement work request signal transmitted from the remote monitoring device 600 via the telephone line.

In FIG. 15, while an example of the image forming system where the printers, the remote monitoring device 600, and the order acceptance terminal 610 can communicate with each other via the telephone line as the communication line is shown, other communication lines can be also used. For example, the Internet line and wireless line can be used.

The lifetime management device in the image forming system manages service life information of photoconductor units (2Y, 2C, 2M, and 2K), the developing units (7Y, 7C, 7M, and 7K), Y, M, C, and K developers, the transfer unit (40), and the fixing unit (60) as parts in the respective printers.

Various variables shown in the following Table 1 are stored in the RAM 200b of the controller 200 in the printer.

TABLE 1

Variable	
t(i)	Unit operating time [days]
D(i)	Unit driving distance [mm]
P(i)	Number of prints [sheets]
Ld(i)	Lifetime driven distance [mm]
Lp(i)	Lifetime print volume [sheets]
T1(i)	Distance remaining lifetime [days]
T2(i)	Sheet remaining lifetime [days]
T3(i)	Unit remaining lifetime [days]
X(i)	Replacement index [days]
Y(i)	Order determining added value [days]

In Table 1, unit operating time t(i) [days] is the accumulated operating time of each unit (including developer) after its replacement (elapsed time since replacement to the present); driven distance D(i) [mm] is the moving distance of each moving member (rollers and belt) in each unit after its replacement to the present, and indicates a characteristic as operation record; number of prints P(i) [sheets] is the number of prints after replacement of each unit to the present; lifetime driven distance Ld(i) [mm] is a lifetime index that is compared to the driven distance D(i) to determine the remaining lifetime of each unit (when the driven distance D(i) reaches the lifetime driven distance Ld(i), the unit is determined to be at the end of its service life); lifetime print volume Lp(i) [sheets] is the number of prints or sheets that can be printed during the lifetime of each unit, i.e., a lifetime index that is compared to the number of prints P(i) to determine the remaining lifetime of each unit (when the number of prints P(i) reaches the lifetime print volume Lp(i), the unit is determined to be at the end of its service life); distance remaining lifetime T1(i) [days] is a remaining lifetime based on a difference between the driven distance D(i) and the lifetime driven distance Ld(i); sheet remaining lifetime T2(i) [days] is a remaining lifetime based on a difference between the number of prints P(i) and the lifetime print volume Lp(i); unit remaining lifetime T3(i) [days] is shorter one of either the distance remaining lifetime T1(i) or the sheet remaining lifetime T2(i); and replacement index X(i) [days] is an index to determine whether to replace each unit.

15

Variables in these nine items are individually set for each unit. The number of units in which the life information is managed is 16, that is, the four photoconductor units (2Y, 2C, 2M, and 2K), the four developing units (7Y, 7C, 7M, and 7K), Y, M, C, and K developers, the transfer unit 40, the belt cleaning unit 42, the secondary transfer unit, and the fixing unit 60. Accordingly, 144 variables (nine items×16) are set. In respective variables, (i) indicates the type of unit, and the value thereof and the unit type have a relationship shown in the following Table 2.

TABLE 2

i value	Name of parts
1	Y photoconductor unit
2	C photoconductor unit
3	M photoconductor unit
4	K photoconductor unit
5	Y developing unit
6	C developing unit
7	M developing unit
8	K developing unit
9	Y developer
10	C developer
11	M developer
12	K developer
13	Transfer unit
14	Belt cleaning unit
15	Secondary transfer unit
16	Fixing unit

Among the variables of nine items, unit operating time $t(i)$, driven distance $D(i)$, number of prints $P(i)$, distance remaining lifetime $T1(i)$, sheet remaining lifetime $T2(i)$, and unit remaining lifetime $T3(i)$ are specific values for each individual product of the unit. When the unit is replaced, an eigenvalue of the old unit must be changed to an eigenvalue of the new unit. Therefore, the controller 200 monitors detachment of the 16 units relative to the printer based on the output value from respective sensors, and when detachment of any unit is detected, the controller 200 performs a replacement inquiry process for the unit. Specifically, when detachment of, for example, the process unit 1C is detected, the controller 200 inquires of the replacement operator whether the photoconductor unit 2C and the developing unit 7C have been replaced, according to a screen display on the operation display unit 206. When a response (a key input operation) from the replacement operator with respect to the inquiry is Yes for the photoconductor unit 2C, the controller 200 updates the C photoconductor unit operating time $t(2)$, the driven distance $D(2)$ of the C photoconductor unit, and the number of prints of the C photoconductor unit $P(2)$ to zero, respectively. Further, the controller 200 resets the distance remaining lifetime $T1(2)$, the sheet remaining lifetime $T2(2)$, and the remaining lifetime $T3(2)$ of the C photoconductor unit, respectively, to predetermined initial values.

While replacement of the unit is ascertained based on detachment detection of the unit and the replacement inquiry processing, there is another method such that an IC chip that stores unit ID number is loaded on respective units and the unit ID number of each unit is monitored by the controller 200, to ascertain the replacement of the unit based on a change of the unit ID number.

Further, various variables can be reset by an input operation by the replacement operator who has replaced the unit on the operation display unit 206, instead of ascertaining the replacement of the unit by the controller 200. However, in this case, there is a possibility that the unit life information

16

becomes inappropriate because the replacement operator forgets to perform a reset operation.

The controller 200 adds 1 to the unit operating time $t(i)$ stored in the RAM 200b for respective units (including the developer), to update the unit operating time $t(i)$ everyday at a predetermined timing.

The driven distances $D(i=1 \text{ to } 4)$ of the Y, C, M, and K photoconductor units are updated in the following manner. That is, a time from the start to the end of an operation is counted for the process drive motors 120Y, 120C, 120M, and 120K. When timing has finished, the timing result is multiplied by a predetermined coefficient to convert the photoconductor-unit driven time [sec] to the surface moving distance [mm] of the photosensitive drum, and the conversion result is added to the driven distances $D(i=1 \text{ to } 4)$ of the Y, C, M, and K photoconductor units up to that time.

The printer in the image forming system changes over a print speed mode between a high-speed print mode in which the photoconductors, rollers, and belts are driven at a relatively high speed so that priority is given to printing speed rather than image quality, and a low-speed print mode in which the photosensitive drums and the like are driven at a relatively low speed so that priority is given to the image quality rather than the printing speed. When the photoconductor-unit driven time is converted to the photosensitive drum surface moving distance, a coefficient corresponding to each mode is used. The coefficient is properly used for other units (the developing unit, etc.) in the same manner.

The printer in the image forming system basically turns on/off the drive of the photoconductor units 2Y, 2C, 2M, and 2K simultaneously. However, when a monochrome image is printed, only the K photoconductor unit is driven. Therefore, the driven distance $D(i)$ becomes largely different between the photoconductor unit 2K and the photoconductor units 2Y, 2C, and 2M for other colors. Further, the photoconductor units 2Y, 2C, and 2M are turned on and off simultaneously at all times, and therefore, their driven distance $D(i)$ are basically supposed to be the same, but can be occasionally different. For example, among these four photoconductor units 2Y, 2C, 2M, and 2K, when only the photoconductor unit 2C has a failure due to an unexpected reason, only the photoconductor unit 2C is replaced. Consequently, after the replacement, the driven distance $D(i)$ of the photoconductor unit 2C is different from that of the photoconductor units 2Y and 2M. Therefore, the driven distance $D(i)$ is calculated separately. The same thing applies to the developing units 7Y, 7C, 7M, and 7K and the developer.

The driven distances $D(i=5 \text{ to } 8)$ of the Y, M, C, and K developing units are updated by the controller 200 in the following manner. That is, the time from the start to the end of the operation is counted for the developing clutches 127Y, 127C, 127M, and 127K. When the timing has finished, the timing result is multiplied by a predetermined coefficient to convert the developing unit driven time [sec] to the surface moving distance [mm] of the developing sleeve, and the conversion result is added to the driven distances $D(i=5 \text{ to } 8)$ of the Y, C, M, and K developing units up to that time.

The driven distances $D(i=9 \text{ to } 12)$ of the Y, M, C, and K developers are updated by employing the surface moving distance (same as that of the developing sleeve) of the screw of the developing unit as an alternative characteristic, according to the following manner. That is, the time from the start to the end of the operation is counted for the developing clutches 127Y, 127C, 127M, and 127K. When the timing has finished, the timing result is multiplied by a predetermined coefficient to convert the developer driven time [sec] to the surface moving distance [mm] of the screw, and the conversion result

is added to the driven distances $D(i=9 \text{ to } 12)$ of the Y, M, C, and K developers up to that time.

The screw and the developing sleeve are turned on/off simultaneously at all times, and the surface migration thereof is synchronized with each other. However, the developing unit and the developer have different driven distance $D(i)$ due to the reason explained below. That is, since the developer has different lifetime from that of the developing unit, in the printer of the image forming system, the replacement cycle of the developer is set to be shorter than that of the developing unit (a threshold described later is different between the developer and the developing unit).

The controller 200 updates the driven distance $D(13)$ of the transfer unit in the following manner. That is, the time from the start to the end of the operation is counted for the transfer belt motor 208. When the timing has finished, the timing result is multiplied by a predetermined coefficient to convert the driven time [sec] of the transfer unit to the surface moving distance [mm] of the transfer unit, and the conversion result is added to the driven distance $D(13)$ of the transfer unit up to that time.

The driven distance $D(14)$ of the belt cleaning unit is updated by employing not the moving distance of the cleaning blade 42a itself but the surface moving distance of the intermediate transfer belt 41 contacting the cleaning blade 42a as an alternative characteristic. That is, the time from the start to the end of the operation is counted for the transfer belt motor 208. When the timing has finished, the timing result is multiplied by a predetermined coefficient to convert the blade driven time [sec] to the surface moving distance [mm] of the blade, and the conversion result is added to the driven distance $D(14)$ of the belt cleaning unit up to that time.

The controller 200 updates the driven distance $D(15)$ of the secondary transfer unit in the following manner. That is, the time from the start to the end of the operation is counted for the secondary transfer motor 209. When the timing has finished, the timing result is multiplied by a predetermined coefficient to convert the driven time [sec] of the secondary transfer unit to the moving distance [mm] of the secondary transfer roller, and the conversion result is added to the driven distance $D(15)$ of the secondary transfer unit up to that time.

The controller 200 updates the driven distance $D(16)$ of the fixing unit in the following manner. That is, the time from the start to the end of the operation is counted for the fixing motor 210. When the timing has finished, the timing result is multiplied by a predetermined coefficient to convert the driven time [sec] of the fixing unit to the moving distance [mm] of the fixing belt, and the conversion result is added to the driven distance $D(16)$ of the fixing unit up to that time.

The controller 200 that updates the driven distance $D(i)$ of each unit functions as an operation counting unit that counts the unit operating time, i.e., the operation time of each unit, and converts the unit operating time to the driven distance $D(i)$ as the operation record of the unit.

The number of prints of the unit $P(i=1 \text{ to } 16)$ in each unit is updated by adding 1 to the number of prints of the unit $P(i=1 \text{ to } 16)$ up to that time, every time when a countup-signal is received once from the print counter 205. In other words, in the printer in the image forming system, a combination of the print counter 205 and the controller 200 functions as a timing unit of the number of prints. The number of prints $P(i)$, which is the number of recording paper sheets P on which an image is formed by the printer, is then calculated for respective units, i.e., a plurality of types of parts.

The lifetime driven distance $Ld(i=1 \text{ to } 16)$ and the replacement index $X(i=1 \text{ to } 16)$ in each unit have a characteristic as a constant rather than a variable. However, due to some rea-

sons, there is a possibility that these can be updated or corrected by a key input by an operator. In the image forming system, therefore, these are handled as variables.

FIG. 16 is a flowchart of relevant parts of a replacement request process performed by the controller 200. The replacement request process starts upon start of print job. When a print countup-signal is output from the print counter 205 (Yes at step S1), the number of prints $P(i)$ is updated in the above process for respective units (step S2). It is then determined whether the print job has finished (step S3). When the print job has not finished (No at step S3), the process returns to step S1. Accordingly, the number of prints $P(i)$ is updated for each print job, in a continuous printing operation for continuously printing on a plurality of recording paper.

When the print job has finished (Yes at step S3), after a unit variable i expressing the unit type is reset to zero (step S4), 1 is added to the unit variable i (step S5). The driven distance $D(i)$ is then updated by the above process (step S6). For example, when the unit variable i is 1, the driven distance $D(1)$ of the Y photosensitive drum is updated. Subsequently, after a print count correction process is performed at step S7, the process from step S8 is performed. The print count correction process is described later in detail.

When the print count correction process is performed at step S7, the distance remaining lifetime $T1(i)$ is calculated based on the following relational expression: $T1(i) = \{Ld(i) - D(i)\} / \{D(i)/t(i)\}$ (step S8).

The sheet remaining lifetime $T2(i)$ is then calculated based on a relational expression: $T2(i) = \{Lp(i) - P(i)\} / \{P(i)/t(i)\}$ (step S9), and then the unit-remaining lifetime $T3(i)$ is updated to either smaller value of the distance remaining lifetime $T1$ or the sheet remaining lifetime $T2$ (step S10).

As seen from the relational expression shown at step S8, the distance remaining lifetime $T1(i)$ is obtained by dividing a difference between the lifetime driven distance $Ld(i)$ as the assumed lifetime index and the driven distance $D(i)$ up to the present by an average driven distance per day. That is, the distance remaining lifetime $T1(i)$ is a numerical value estimating how many days are required for the driven distance $D(i)$ to reach the lifetime driven distance $Ld(i)$, based on the accumulated driven distances of the unit up to the present. On the other hand, the sheet remaining lifetime $T2(i)$ is, as seen from the relational expression shown at step S9, obtained by dividing a difference between the lifetime print volume $Lp(i)$ as the assumed lifetime index and the number of prints $P(i)$ up to the present by an average number of prints per day. That is, the sheet remaining lifetime $T2(i)$ is a numerical value estimating how many days are required for the number of prints $P(i)$ to reach the lifetime print volume $Lp(i)$, based on the current accumulated number of prints.

While it suffices that only one of the distance remaining lifetime $T1(i)$ and the sheet remaining lifetime $T2(i)$ is calculated and designated as the unit-remaining lifetime, but in the image forming system, as shown at step S10, the shorter one of $T1(i)$ and $T2(i)$ is designated as the unit-remaining lifetime $T3(i)$. Accordingly, a worn-out unit is doubly monitored, to further increase the determination accuracy.

When the unit remaining lifetime $T3(i)$ is updated, it is then determined whether the unit remaining lifetime $T3(i)$ has reached a predetermined replacement index $X(i)$ (step S11). If the replacement index $X(i)$ is set, for example, to 45 [days], it is determined that "the unit will wear out soon" 45 days prior to the day when the unit is estimated to wear out. If such a determination is not made (No at step S11), in other words, when it is determined that there is enough time until the service life of the unit ends, it is then determined whether the

unit variable i is 16, that is, life estimation has been performed with respect to all types of units (step S13). When the unit variable i is not 16 (No at step S13), the process returns to step S5. Accordingly, life estimation is performed for the next unit.

On the other hand, at step S11, if it is determined that "the unit will wear out soon" (Yes at step S11), after a replacement request flag $F1(i)$ is set for the unit (step S12), the step S13 is performed.

Thereafter, when it is determined that the unit variable i is 16 at step S13, that is, when life estimation has been performed with respect to all types of units, it is then determined whether any one of the replacement request flags $F1(1)$ to $F1(16)$ is being set (step S14). When it is determined that no replacement request flag is being set (No at step S14), the continuous process finishes. On the other hand, when it is determined that a replacement request flag is being set (Yes at step S14), it is determined whether a previous report flag $F2(i)$ is being set for the unit (step S15).

The previous report flag $F2(i)$ is set when the unit corresponding to the unit variable i transmits a replacement request signal indicating that replacement is necessary to the remote monitoring device 600, and released when the replacement of the unit is made. When there is a unit with the previous report flag $F2(i)$ being set (Yes at step S15), the replacement request signal was transmitted for the unit in the past. Therefore, the continuous process finishes without transmitting the replacement request signal for the unit. On the other hand, when the previous report flag $F2(i)$ is not set for all the units (No at S15), the replacement request signal for the unit, for which replacement of the unit is required, and a signal of the unit remaining lifetime $(u)T3(i)$ for all other units are transmitted from the modem 207 as a transmitter to the remote monitoring device via the telephone line (step S16). After the previous report flag $F2(i)$ is set for the unit (step S17), the continuous process finishes. The reason why the unit remaining lifetime is expressed as $(u)T3(i)$ instead of $T3(i)$ is that not only the information of the unit remaining lifetime but also an individual user ID (or printer ID) added to each user are transmitted at the same time at step S16. The sign u expresses the user ID (or printer ID). Since the user ID information is transmitted at the same time, the remote monitoring device having received the signal can specify in which unit of which user the replacement request has been issued.

The controller 200 that performs such a replacement request process calculates the unit-remaining lifetime $T3(i)$ for each unit based on the number of prints $P(i)$ as the number of records by part and the lifetime print volume $Lp(i)$ as the lifetime index. The controller 200 also determines whether replacement of each unit is necessary based on the calculation result by the remaining lifetime calculator, and the distance remaining lifetime $T1(i)$ and the sheet remaining lifetime $T2(i)$ as predetermined replacement indices. Further, the controller 200 measures the unit operating time $t(i)$ and the driven distance $D(i)$, which are operation amounts by parts specific to each unit.

FIG. 17 is a flowchart of the print count correction process at step S7 in FIG. 16. First, it is determined whether the unit corresponding to the unit variable i is the operation amount-dependent deteriorated part (step S7a). In the printer of the image forming system, the photoconductor units 2Y, 2C, 2M, and 2K respectively include the photosensitive drums 3Y, 3C, 3M, and 3K, which do not closely contact the recording paper P during the print job, are the operation amount-dependent deteriorated parts. Further, the developing units 7Y, 7C, 7M, and 7K include the developing sleeve and the screw, which are not closely contacting with the recording paper P , are the

operation amount-dependent deteriorated parts. On the other hand, the transfer unit 40 include the intermediate transfer belt 41 closely contacted to the recording paper P during the print job is the print volume-dependent deteriorated part. Further, the belt cleaning unit 42 including the cleaning blade 42a for scraping paper dust adhered to the intermediate transfer belt 41 as the endless movable body is the print volume-dependent deteriorated part. The secondary transfer unit including the secondary transfer roller 50 closely contacted to the recording paper P is also the print volume-dependent deteriorated part. The fixing unit 60 including the fixing belt 64 closely contacted to the recording paper P is also the print volume-dependent deteriorated part.

When the unit corresponding to the unit variable i is the operation amount-dependent deteriorated part (Yes at step S7a), a distance ratio $\alpha(i)$ is calculated according to a relational expression as follows: distance ratio $\alpha(i)$ =standard distance $Sd(i)$ × number of prints $P(i)$ / driven distance $D(i)$ (step S7b). It is then determined whether the distance ratio $\alpha(i)$ exceeds a predetermined ratio threshold $C(i)$ (step S7c). When the distance ratio $\alpha(i)$ exceeds a predetermined ratio threshold $C(i)$ (Yes at step S7c), the number of prints $P(i)$ is corrected in the following manner (step S7d). That is, the number of prints $P(i)$ is corrected according to a relational expression as follows: $P(i)=P(i)+sheet count coefficient a \times \{distance ratio \alpha(i)-ratio threshold C(i)\}$. The sheet count coefficient a in this relational expression is a constant determined based on results of preliminary tests. Since the difference between the distance ratio $\alpha(i)$ and the ratio threshold $C(i)$ is multiplied by the sheet count coefficient a , the number of prints corresponding to the difference is added to the number of prints $P(i)$. Accordingly, with a user who performs the single printing operation relatively frequently, when the driven distance $D(i)$ as the operation amount by parts increases considerably, although the number of prints $P(i)$ is relatively small, the number of prints $P(i)$ is corrected to a value corresponding to the driven distance $D(i)$. The unit-remaining lifetime $T3(i)$ is then calculated for the photoconductor units and the developing units as the operation amount-dependent deteriorated parts, reflecting both the driven distance $D(i)$ and the number of prints $P(i)$. Therefore, life estimation of the photoconductor units and the like can be performed more accurately than a case that only the driven distance $D(i)$ is reflected on the unit-remaining lifetime $T3(i)$, or a case that only the number of prints $P(i)$, which is inappropriately small compared to the driven distance $D(i)$, is reflected on the unit-remaining lifetime $T3(i)$.

On the other hand, at step S7a, when it is determined that the unit variable i corresponds to the operation amount-dependent deteriorated part (No at step S7a), the process proceeds to step S8 in FIG. 16 without correcting the number of prints $P(i)$. Further, even when it is determined that the unit variable i corresponds to the operation amount-dependent deteriorated part, when it is determined that the distance ratio $\alpha(i)$ does not exceed the ratio threshold $C(i)$ at step S7c (No at step S7c), the process proceeds to step S8 in FIG. 16 without correcting the number of prints $P(i)$.

FIG. 18 is a flowchart of relevant parts of a remaining lifetime informing process performed by the controller 200. The remaining lifetime informing process is performed everyday at a predetermined time. First, the unit variable i is reset to zero (step S1), and 1 is added to the unit variable i (step S2). It is then determined whether the previous report flag $F2(i)$ is being set (step S3). When the previous report flag $F2(i)$ is being set, the replacement request has already been issued in the unit corresponding to the unit variable i , and the replacement request signal for the unit has been already trans-

mitted to the remote monitoring device. In such a case (Yes at step S3), a signal of the unit-remaining lifetime $(u)T3(i)$ for all the units not corresponding to the unit variable i is transmitted to the remote monitoring device (step S5). Thus, when a replace request is issued in any unit, the unit-remaining lifetime $(u)T3(i)$ of all other units is regularly transmitted to the remote monitoring device everyday at step S5, until the replacement work of the unit is completed.

When it is determined that the previous report flag $F2(i)$ is not being set (No step S3), it is then determined whether the unit variable i is 16, and when the unit variable i is not 16, the process returns to step S2. It is then determined whether the previous report flag $F2(i+1)$ is being set for the next unit $(i+1)$.

The remote monitoring device 600 installed in the maintenance service center has a modem as a communication unit, a CPU as a calculation unit, a display, and an RAM, an ROM, and a hard disk. When a signal transmitted from the printers via the telephone line is received by the modem as the communication unit, various types of data processing are performed based on the signal.

FIG. 19 is a flowchart of relevant parts of a replacement order process performed by the remote monitoring device 600. When a replacement request signal is received from any printer connected to the remote monitoring device 600 via the telephone line (Yes step S1), a unit order flag $(u)F3(i)$ for the unit in the printer (user) is set (step S2). It is then determined in the subsequent process that it is necessary to order the replacement work of the unit corresponding to the unit variable i in the printer (u) , according to the setting of the unit order flag $(u)F3(i)$.

Further, when a signal of the unit-remaining lifetime $(u)T3(i)$, which does not include the replacement request signal from some printer connected to the remote monitoring device 600 via the telephone line, is received (Yes at step S3), the unit-remaining lifetime $(u)T3(i)$ already stored in the hard disk is replaced by a new one (step S4). Accordingly, the unit-remaining lifetime $(u)T3(i)$ for other units regularly transmitted everyday from the printer, in which the replacement request has been issued for some unit, is regularly updated everyday in the remote monitoring device.

Thereafter, steps S5 and S6 are performed (these are explained later) for easier understanding. Steps S7 to S13 forms a step group, at which various kinds of determination processes are performed for units, for which the unit order flag $(u)F3(i)$ is not set at step S2, in other words, units in which the replacement request has not yet been issued.

At steps S7 to S13, at first, after the unit variable i is reset to zero (step S7), 1 is added to the unit variable i (step S8). It is then determined whether the unit order flag $(u)F3(i)$ corresponding to the unit variable i is being set (step S9). Due to a reason described below, when it is determined that the unit order flag $(u)F3(i)$ is being set (Yes at step S9), the unit variable i at that time corresponds to the unit for which the unit order flag $(u)F3(i)$ has been set at step S2. In such a case, the process returns to step S8, and 1 is added to the unit variable i to perform determination for the next unit.

On the other hand, when the unit order flag $(u)F3(i)$ is not set (No at step S9), an order determination threshold $Z(i)$ is set to a value obtained by adding an order determining additional value $Y(i)$ to the replacement index $X(i)$ (step S10). The order determination threshold $Z(i)$ is a threshold for determining the necessity of order for replacement work, and is set in unit of day for each type of unit. The replacement index $X(i)$ is the same as the one used in the replacement request process shown in FIG. 16. As explained above, the replacement index $X(i)$ is for determining whether the unit-remaining lifetime $T3(i)$ is within a predetermined time. For example, in the case

of a unit in which it is desired to issue a replacement request 45 [days] prior to the day when the unit is estimated to wear out, the replacement index $X(i)$ is set to 45 days. On the other hand, the order determining additional value $Y(i)$ indicates 5 time [days] up to a point in time dated back slightly from a point in time when it is desired to issue a replacement request. The replacement request is issued at a point in time dated back by the replacement index $X(i)$ from the day when the unit is estimated to wear out, however, the order determination threshold $Z(i)$ is set to $Z(i)=X(i)+Y(i)$ to determine whether 10 the requirement for issuing the replacement request is satisfied (whether the unit-remaining lifetime is within the range) even if the replacement index $X(i)$ is extended slightly longer. At the next step S11, it is determined whether the unit-remaining lifetime $(u)T3(i)$ is equal to or less than the order determination threshold $Z(i)$.

When the unit-remaining lifetime $(u)T3(i)$ is longer than the order determination threshold $Z(i)$ (No at step S11), it means that the replacement request is not issued even if the 20 replacement index $X(i)$ is extended slightly longer than the original value. In such a case, the determination process for the unit corresponding to the unit variable i finishes (No at step S13), and the determination process for the next unit corresponding to the unit variable i is performed (steps S8 to 25 S11). On the other hand, when the unit-remaining lifetime $(u)T3(i)$ is equal to or less than the order determination threshold $Z(i)$ (Yes at step S11), it means that the replacement request is issued if the replacement index $X(i)$ is extended slightly longer than the original value. In such a case, after an 30 order suspension flag $(u)F4$ corresponding to the user variable u is set (step S12), the continuous process returns to the initial step. The order suspension flag $(u)F4(i)$ is a flag for suspending the order of replacement work with respect to the unit in which the unit order flag $(u)F3(i)$ is set.

In other words, in the step group of steps S7 to S13, it is determined whether the requirement for issuing the replacement request is satisfied when the replacement index $X(i)$ is extended slightly longer than the original value, with respect to units other than the unit in which the replacement request 40 has been already issued. When the requirement is satisfied in some unit, the order suspension flag $(u)F4(i)$ is set therein, and the order of replacement work with respect to the unit in which the replacement request has been already issued is suspended. At this time, the unit order flag $(u)F3(i)$ for the unit 45 in which the replacement request has been already issued is remained in the set state (step S2).

On the other hand, when the requirement for issuing the replacement request is not satisfied even if the replacement index $X(i)$ is extended slightly longer than the original value, 50 in all the units other than the unit in which the replacement request has been already issued (Yes at step S13), the replacement work is ordered for the unit. Specifically, a replacement-work order signal for the unit in which the replacement request has been already issued is transmitted to the order acceptance terminal 610 in the parts center from the modem 55 of the remote monitoring device via the telephone line (step S14). Accordingly, a replacement worker is dispatched from the parts center to the user to replace the unit in which the replacement request has been issued. Upon transmission of the replacement-work order signal, all the unit order flags $(u)F3(i)$ being set are released.

As explained above, when the replacement request signal transmitted from the user printer is received at step S1, the unit order flag $(u)F3(i)$ is set for the unit of the user, in which 60 the replacement request has been issued (step S2). It is then determined whether the order suspension flag $(u)F4(i)$ is being set (step S5). When the order suspension flag $(u)F4(i)$ is

being set, a replacement request issued in the past in a unit other than the unit in which the unit order flag (u)F3(i) has been set at step S2 immediately before, and the unit order flag (u)F3(i) has been already set as well for the unit. However, the replacement work for that unit is suspended due to setting of the order suspension flag (u)F4(i), and hence the order has not been placed yet. In other words, when it is determined that the order suspension flag (u)F4(i) is being set at step S5, the condition is as described below. That is, although a replacement request issued in the past for a certain unit, it was estimated that a replacement request for another unit separate from the unit would be issued soon, and hence the order of the replacement work for the former unit was suspended and then the replacement request for the latter unit had just been issued. Therefore, in such a case (Yes at step S5), after the order suspension flag (u)F4(i) is released (step S6), a replacement-work order signal for these units is transmitted to the order acceptance terminal in the parts center.

When the controller 200 in the printer as the replacement-request determining unit determines that replacement is required for some unit, the remote monitoring device 600 that performs such a replacement order process as an order-timing determining unit that determines a replacement-work order timing for the unit based on the unit-remaining lifetime (u)T3(i) in other units.

The respective processes shown in FIGS. 16, 17, 18, and 19 can be consolidated as follows. That is, in the printer under control of the user, the unit-remaining lifetime (u)T3(i) is calculated based on the number of prints P(i) and the driven distance D(i), after the number of prints P(i) is corrected to a value corresponding to the driven distance D(i), with respect to the photoconductor units and the developing units, which are the operation amount-dependent deteriorated parts. With respect to the transfer unit and the like, which are the print volume-dependent deteriorated parts, the unit-remaining lifetime (u)T3(i) is calculated based on the driven distance D(i) and the uncorrected number of prints P(i). When a replacement request has been issued in some unit, a replacement request signal for the unit and the unit-remaining lifetime (u)T3(i) for other units are transmitted to the remote monitoring device 600 in the maintenance service center. Thereafter, the printer continuously transmits the unit-remaining lifetime (u)T3(i) for all other units regularly everyday to the remote monitoring device 600, until the replacement of the unit in which the replacement request been issued has finished. On the other hand, upon being informed of the unit-remaining lifetime (u)T3(i) reported regularly everyday from some printer, the remote monitoring device 600 sequentially updates the unit-remaining lifetime (u)T3(i). Upon receiving a replacement request signal transmitted from some printer, the remote monitoring device 600 determines whether the order suspension flag (u)F4 is being set for the printer. When the order suspension flag (u)F4 is not set, that is, if there is no other unit, whose replacement work is suspended in the printer, the remote monitoring device 600 determines whether a replacement request will be issued soon in the units in which the replacement request has not been issued yet at present. If there is a unit in which the replacement request will be issued soon, the order of replacement work for the unit in which the replacement request has already been issued is temporary suspended. If there is no unit in which the replacement request will be issued soon, the replacement work of the unit in which the replacement request has already been issued is ordered immediately. After having received the replacement request signal, when the remote monitoring device 600 determines that the order suspension flag (u)F4 is being set, the remote monitoring device 600 concurrently orders the

replacement work of the unit corresponding to the replacement request signal received immediately before, and the replacement work of another unit, for which the order of replacement work was suspended in the past. Accordingly, since the replacement work of two units in which the replacement request is issued in a relatively short period is ordered concurrently, maintenance work can be performed more efficiently than before.

In the image forming system with this configuration, the controller 200 in the printer, which is the remaining lifetime calculator, corrects the calculation result of the number of prints P(i) for each part based on the driven distance D(i) as an operating distance by parts, with respect to the operation amount-dependent deteriorated parts, which are part of the plurality of types of parts. The controller 200 then calculates the unit-remaining lifetime T3(i) based on the corrected value and the lifetime print volume Lp(i) as the lifetime index.

An example where the controller 200 measures the driven distance D(i), which is an accumulated surface-moving distance, as the operation amount by parts has been explained. However, the controller 200 can also measure the unit driven time, which is the driven time of respective units, and calculate the unit-remaining lifetime T3(i) based on the measurement result.

In the first embodiment, an example has been explained where the controller 200 is configured such that when the distance ratio $\alpha(i)$ exceeds the predetermined ratio threshold C(i) (or can be equal to or larger than the predetermined ratio threshold C(i)), the controller 200 corrects the number of prints P(i) to a larger value. In this configuration, such a situation can be prevented that before it is estimated that the operation amount-dependent deteriorated part will be worn out soon, the operation amount-dependent deteriorated part is worn out. Contrary to such a configuration, the controller 200 can correct the calculation result of the number of prints P(i) to a smaller value when the distance ratio $\alpha(i)$ is less than the predetermined ratio threshold C(i) (or can be equal to or less than the predetermined ratio threshold C(i)). In the case of the first embodiment, such a situation can be prevented that the operation amount-dependent deteriorated part, still having sufficient time until being worn out, is estimated to be worn out soon. The both configurations can be employed together. Specifically, when the distance ratio $\alpha(i)$ exceeds a predetermined first ratio threshold C1(i), the calculation result of the number of prints P(i) is corrected to a larger value, whereas when the distance ratio $\alpha(i)$ is less than a predetermined second ratio threshold C2(i), the calculation result of the number of prints P(i) is corrected to a smaller value (C1(i) > C2(i)).

Modified examples of the image forming system are explained next. The modified examples have the same configuration as previously described for the image forming system of the first embodiment unless otherwise specified.

FIG. 20 is an enlarged view of four photoconductor gears 133Y, 133C, 133M and 133K, and a peripheral configuration thereof in a printer of an image forming system according to a modification of the embodiment. The Y, C, and M photo-sensitive drums in the printer are driven by a photoconductor drive motor exclusive for the photoconductor units, instead of using a process drive motor, which also functions as a drive source of the photoconductor units and the developing units. Further, the three Y, C, and M photoconductor units are driven by one photoconductor drive motor 135YCM, instead of being driven by each exclusive photoconductor drive motor. A drive gear 121YCM fixed to a motor shaft of the photoconductor drive motor 135YCM engages with the photoconduc-

tor gear 133C and the photoconductor gear 133M. Accordingly, the Y photosensitive drum and the M photosensitive drum are rotated.

The photoconductor gear 133C engages with the photoconductor gear 133Y via an idler gear 134. Accordingly, the Y photosensitive drum is rotated via the drive gear 121YCM, the photoconductor gear 133C, the idler gear 134, and the photoconductor gear 133Y.

On the other hand, the K photoconductor unit and the K developing unit are driven by the process drive motor 120K as in the image forming system according to the first embodiment. The drive gear 121K fixed to the motor shaft of the process drive motor 120K engages with the photoconductor gear 133K. Accordingly, the K photosensitive drum is rotated. Although not shown for brevity, the drive gear 121K also engages with the developing gear (not shown), and a rotation driving force of the developing gear is transmitted to the developing unit via the developing clutch (not shown).

The Y, M, and C developing units (not shown) are driven by one developing motor (not shown) that commonly drives these developing units.

In the printer having such a configuration, the driven distances $D(i=1 \text{ to } 3)$ of the Y, C, and M photoconductor units are calculated, respectively, based on the driven time of the one photoconductor drive motor 135YCM. However, since there is a possibility that one or two photoconductor units of the Y, C, and M three photoconductor units can be unexpectedly replaced due to a failure or the like, the driven distances $D(i=1 \text{ to } 3)$ of the photoconductor units are calculated separately for each color. The number of prints of the Y, C, and M photoconductor units $P(i=1 \text{ to } 3)$ is also calculated separately for each color of Y, C, and M, due to the same reason.

The driven distances $D(i=5 \text{ to } 7)$ of the Y, C, and M developing units, and the driven distances $D(i=9 \text{ to } 11)$ of the Y, C, and M developers are calculated based on the driven time of one developing motor. However, since there is a possibility that one or two developing units of the three (Y, C, and M) developing units can be unexpectedly replaced due to a failure or the like, the driven distances of the developing units and the driven distances of the developers are calculated separately for each color. The number of prints of the developing units $P(i=5 \text{ to } 7)$ is also calculated separately for each color of Y, C, and M, due to the same reason.

The driven distance D(4) of the K photoconductor unit, the driven distance D(8) of the K developing unit, and the driven distance D(12) of the K developer are calculated by the same process as in the first embodiment.

When a replacement request is issued in some unit, the controller of the printer itself can determine whether to order the unit, and also functions as an order-timing determining unit. Therefore, the controller does not transmit an order request signal and the unit remaining lifetime (u)T3(i) of other units to the remote monitoring device, even when the replacement request is issued. When the requirement for ordering the replacement work is satisfied, the controller itself transmits a replacement-work order signal of the unit to the order acceptance terminal in the part service center. However, when an emergency call has been made, the controller transmits the signal to the remote monitoring device.

An image forming system according to a second embodiment of the present invention is explained next. The image forming system of the second embodiment is basically of the same configuration and operates in a similar manner as that of the first embodiment. Accordingly, the same description is not repeated herein.

In the image forming system, the controller 200 of the printer performs the remaining lifetime informing process

and the replacement order process in the same manner as previously described in connection with FIGS. 17 and 19.

FIG. 21 is a flowchart of relevant parts of the replacement request process performed by the controller 200 of the second embodiment. When comparing the flowchart with that of the image forming system according to the first embodiment shown in FIG. 16, it is different in that after the sheet remaining lifetime $T2(i)$ is calculated, a $T2(i)$ correction process for correcting this is performed, instead of performing the print count correction process after updating the driven distance $D(i)$. In other words, in this image forming system, after the sheet remaining lifetime $T2$ is calculated without correcting the number of prints $P(i)$, the calculation result thereof is corrected (step S9).

FIG. 22 is a detailed flowchart of the remaining lifetime correction process shown in FIG. 21. In the process of correcting the remaining-time $T2(i)$, it is determined whether the unit corresponding to the unit variable i is the operation amount-dependent deteriorated part (step S9a). When the unit corresponding to the unit variable i is the operation amount-dependent deteriorated part (Yes at step S9a), the distance ratio $\alpha(i)$ is calculated based on a relational expression as follows: distance ratio $\alpha(i)$ =standard distance $Sd(i) \times$ number of prints $P(i)$ /driven distance $D(i)$ (step S9b). It is then determined whether the distance ratio $\alpha(i)$ exceeds a predetermined ratio threshold $C(i)$ (step S9c). When the distance ratio $\alpha(i)$ exceeds the predetermined ratio threshold $C(i)$ (Yes at step S9c), the sheet remaining lifetime $T2(i)$ is corrected in the following manner (step S9d). That is, the sheet remaining lifetime $T2(i)$ is corrected by a relational expression as follows: $T2(i)=T2(i)+\text{life coefficient } b \times \{\text{distance ratio } \alpha(i)-\text{ratio threshold } C(i)\}$. The life coefficient b in the relational expression is a constant determined based on results of pre-tests. Since a difference between the distance ratio $\alpha(i)$ and the ratio threshold $C(i)$ is multiplied by the life coefficient b , a lifetime corresponding to the difference is subtracted from the sheet remaining lifetime $T2(i)$. Accordingly, with a user who frequently performs a single print operation, when the driven distance $D(i)$ as the operation amount by parts considerably increases, although the number of prints $P(i)$ is relatively small, the sheet remaining lifetime $T2(i)$ is corrected to a value corresponding to the driven distance $D(i)$. Accordingly, with respect to the photoconductor units and the developing units, both the driven distance $D(i)$ and the number of prints $P(i)$ are reflected on the unit-remaining lifetime $T3(i)$. Accordingly, the end of service life of the photoconductor units and the like can be accurately estimated, than in a case that only the driven distance $D(i)$ is reflected on the unit-remaining lifetime $T3(i)$, or only the number of prints $P(i)$, which becomes inappropriately small as compared to the driven distance $D(i)$, is reflected on the unit-remaining lifetime $T3(i)$.

On the other hand, when it is determined that the unit variable i corresponds to the print volume-dependent deteriorated part at step S9a (No at step S9a), the process proceeds to step S10 in FIG. 21 without correcting the sheet remaining lifetime $T2(i)$. Even when it is determined that the unit variable i corresponds to the operation amount-dependent deteriorated part, when it is determined that the distance ratio $\alpha(i)$ does not exceed the ratio threshold $C(i)$ (No at step S9c), the process proceeds to step S10 in FIG. 21 without correcting the number of prints $P(i)$.

In the second embodiment, an example where the controller 200 corrects the calculation result of the sheet remaining lifetime $T2(i)$ to a larger value when the distance ratio $\alpha(i)$ exceeds the predetermined ratio threshold $C(i)$ (or can be equal to or larger than the predetermined ratio threshold $C(i)$)

has been explained. In this configuration, such a situation can be prevented that before it is estimated that the operation amount-dependent deteriorated part will be worn out soon, the operation amount-dependent deteriorated part is worn out. Contrary to such a configuration, the controller 200 can correct the calculation result of the sheet remaining lifetime $T2(i)$ to a smaller value when the distance ratio $\alpha(i)$ is less than the predetermined ratio threshold $C(i)$ (or can be equal to or less than the predetermined ratio threshold $C(i)$). In this case, such a situation can be prevented that the operation amount-dependent deteriorated part, still having sufficient time until being worn out, is estimated to be worn out soon. The both configurations can be employed together. Specifically, when the distance ratio $\alpha(i)$ exceeds the predetermined first ratio threshold $C1(i)$, the calculation result of the sheet remaining lifetime $T2(i)$ is corrected to a larger value, whereas when the distance ratio $\alpha(i)$ is less than the predetermined second ratio threshold $C2(i)$, the calculation result of the sheet remaining lifetime $T2(i)$ is corrected to a smaller value ($C1(i) > C2(i)$).

As in the modification explained above, the function as replacement operation order timing can be exhibited by the controller 200 of the printer, instead of using the remote monitoring device.

While the image forming system equipped with the printer that forms color images by the process units for different colors has been explained, the present invention is also applicable to an image forming system equipped with an image forming apparatus that forms only monochrome images.

In the image forming system according to the first embodiment, the controller 200 as the remaining lifetime calculator corrects the calculation result of the number of prints $P(i)$ by the controller 200 as the recording-number timing unit, based on the driven distance $D(i)$ as the operation amount by parts, and calculate the unit-remaining lifetime $T3(i)$ based on the corrected value and the lifetime print volume $Lp(i)$ as the lifetime index. Because the number of prints $P(i)$ is corrected to a value corresponding to the driven distance $D(i)$, such a situation can be prevented that the operation amount-dependent deteriorated part is worn out before it is estimated that the part will be worn out soon, or that the operation amount-dependent deteriorated part still having sufficient time until being worn out is estimated to be worn out soon.

Further, the controller 200 as the number-of-prints correcting unit is configured such that when the ratio of the driven distance $D(i)$ to the standard operating value by parts ($Sd(i) \times P(i)$) calculated by multiplying the number of prints $P(i)$ by the standard distance $Sd(i)$ as the predetermined coefficient (the distance ratio $\alpha(i)$) is equal to or larger than the predetermined ratio threshold $C(i)$, or exceeds the ratio threshold $C(i)$, the number of prints $P(i)$ is corrected to a larger value than the calculation result calculated by the recording-number timing unit. In such a configuration, only when the ratio of the driven distance $D(i)$ to the number of prints $P(i)$ is equal to or larger than the predetermined ratio, the number of prints $P(i)$ can be corrected to a value corresponding to the driven distance $D(i)$.

Still further, the controller 200 is configured such that while the sheet remaining lifetime $T2(i)$ as a first remaining lifetime is calculated based on the corrected value of the number of prints $P(i)$ and the lifetime print volume $Lp(i)$, the distance remaining lifetime $T1(i)$ as a second remaining lifetime is calculated based on the driven distance $D(i)$ and the lifetime print volume $Lp(i)$, and the controller 200 designates either shorter lifetime as the unit-remaining lifetime $T3(i)$. That is, either shorter one of the sheet remaining lifetime $T2(i)$ of an appropriate value corresponding to the driven

distance $D(i)$ and the distance remaining lifetime $T1(i)$ corresponding to the driven distance $D(i)$ is designated as the unit-remaining lifetime $T3(i)$. As a result, a situation can be prevented that a replacement request is issued after the parts 5 is worn out as compared to a case that either one is designated as the unit-remaining lifetime.

It is desired to constitute the controller 200 to correct the number of prints $P(i)$ within a predetermined upper limit range. Specifically, in FIG. 17, a determination step of determining whether the corrected $P(i)$ exceeds a predetermined upper limit, and when the corrected $P(i)$ exceeds the predetermined upper limit, a step of correcting the corrected $P(i)$ to a value same as the upper limit are provided after step S7d. As a result, a situation such that the unit-remaining lifetime $T3(i)$ is extended excessively can be prevented.

In the image forming system according to the second embodiment, the controller 200 as the remaining lifetime calculator corrects the sheet remaining lifetime $T2(i)$ calculated based on the calculation result of the number of prints 10 $P(i)$ and the lifetime print volume $Lp(i)$ based on the driven distance $D(i)$. With this configuration, as in the image forming system according to the first embodiment, such a situation can be prevented that the operation amount-dependent deteriorated part is worn out before it is estimated that the part will be 15 worn out soon, or that the operation amount-dependent deteriorated part still having sufficient time until being worn out is estimated to be worn out soon can be prevented.

In the printer in the image forming system according to the embodiments, the controller 200 functions as a replacement-request determining unit that determines whether replacement is required based on the unit-remaining lifetime $T3(i)$ for respective units, which are various types of parts. In such a configuration, a replacement request for the unit is issued at a timing when the unit-remaining lifetime $T3(i)$ becomes 20 equal to or less than a predetermined replacement index $X(i)$, so that the unit is replaced quickly.

Further, the controller 200 as the number-of-prints correcting unit corrects the number of prints $P(i)$ or the sheet remaining lifetime $T2(i)$ as the remaining lifetime with respect to 25 only the photoconductor units and the developing units, of the respective units, which are parts whose deterioration depends on the driven distance $D(i)$ rather than the number of prints $P(i)$. Thus, it can be prevented that the life estimation date becomes inappropriate due to correction of the number of 30 prints $P(i)$ and the sheet remaining lifetime $T2(i)$ of the transfer unit and the fixing unit, which are the print volume-dependent deteriorated parts, to a value corresponding to the driven distance $D(i)$.

Information on the number of prints $P(i)$ as the number of 35 records by part and the driven distance $D(i)$ as the operation amount by parts in the controller 200 can be stored in an information storage unit such as an IC chip provided in each unit, and the controller 200 as a recording-number timing unit and measuring unit can read or update the data. According to 40 such a configuration, even when the unit being used is replaced in a plurality of printers, the unit-remaining lifetime $T3$ can be calculated in each printer based on the appropriate number of prints $P(i)$ and driven distance $D(i)$.

The image forming system includes an image forming 45 apparatus which has a photosensitive drum as a latent image carrier that carries a latent image on the endlessly moving surface, a developing sleeve that obtains a toner image as a visible image by developing the latent image on the photosensitive drum with a developer carried on the endlessly moving surface, the transfer unit 40 that transfers the toner image on the photosensitive drum onto the endlessly moving intermediate transfer belt 41, and the fixing belt 64 that fixes 50

the toner image on the recording paper P by bringing the endlessly moving surface thereof into close contact with the recording paper P. The controller 200 as the remaining lifetime calculator calculates the unit-remaining lifetime $T3(i)$ of at least two units of the photosensitive drum, the developing sleeve, the intermediate transfer belt 41, and the fixing belt 64. When it is estimated that a replacement request will be issued within a relatively short period of time for at least two units, these units are replaced at the same time, which enables improvement of the maintenance work.

The controller 200 measures the driven distance $D(i)$, which is the accumulated surface-moving distance, as the operation amount by parts, of the photosensitive drum, the developing sleeve, the intermediate transfer belt 41, and the fixing belt 64. The controller 200 also calculates the remaining lifetime of these parts based on the driven distance $D(i)$ and the lifetime driven distance $Ld(i)$. Thus, the service life of respective parts can be ascertained based on the driven distance.

The cleaning blade 42a cleans the surface of the intermediate transfer belt 41 as the endlessly moving body, while contacting the surface thereof, and the controller 200 calculates the unit-remaining lifetime $T3(14)$ of the cleaning blade 42a (the belt cleaning unit) based on the driven distance $D(14)$ as the accumulated surface-moving distance of the intermediate transfer belt 41 and the distance remaining lifetime $T1(14)$ as the lifetime index. When the cleaning blade 42a and other parts issue a replacement request within a relatively short period of time, the replacement work with respect to the both units can be performed at the same time, which enables improvement of the maintenance work. Further, as the driven distance of the cleaning blade 42a, whose surface is not endlessly moved, the driven distance of the intermediate transfer belt 41 is used as an alternative characteristic. Thus, it is possible to appropriately determine wear of the blade with an increase of the driven time.

The controller 200 measures the driven distance $D(13)$ of the transfer unit, which is the accumulated surface-moving distance of the intermediate transfer belt 41, as the operation amount by parts. The controller 200 calculates the driven distance $D(14)$ of the cleaning unit, which is the remaining lifetime of the cleaning blade 42a, based on the lifetime driven distance $Ld(13)$ of the transfer unit as the lifetime index. Therefore, wear of the cleaning blade 42a, which is a part whose surface is not endlessly moved, can be ascertained based on the driven distance $D(13)$ of the transfer unit, which is the surface moving distance of the intermediate transfer belt 41 coming in close contact with the cleaning blade 42a. Thus, it is possible to accurately estimate the remaining lifetime of the cleaning blade 42a.

The controller 200 calculates the number of prints $P(i)$ as the number of prints of the parts, which is the accumulated number of the recording paper P on which an image is formed by the printer mounted with the photosensitive drum, the developing sleeve, the intermediate transfer belt 41, and the fixing belt 64, for each of these units. The controller 200 also calculates the sheet remaining lifetime $T2(i)$ as the remaining lifetime of the photosensitive drum, the developing sleeve, the intermediate transfer belt 41, and the fixing belt 64 based on the lifetime print volume $Lp(i)$ as the lifetime index and the number of prints $P(i)$ as the operation amount by parts. Thus, wear of the photosensitive drum, the developing sleeve, the intermediate transfer belt 41, and the fixing belt 64 in each printing operation is ascertained based on the number of prints $P(i)$, which enables accurate life estimation.

The controller 200 counts the unit operating time $t(i)$, which is accumulated operating time of the photosensitive

drum, the developing sleeve, the intermediate transfer belt 41, and the fixing belt 64. The controller 200 as the remaining lifetime calculator calculates the distance remaining lifetime $T1(i)$ and the sheet remaining lifetime $T2(i)$ as the remaining lifetime of the photosensitive drum, the developing sleeve, the intermediate transfer belt 41, and the fixing belt 64, based on the unit operating time $t(i)$ in addition to the driven distance $D(i)$ and the number of prints $P(i)$. Thus, an average increase of the driven distance $D(i)$ and the number of prints $P(i)$ per day can be ascertained based on the unit operating time $t(i)$, and based on this, the distance remaining lifetime $T1(i)$ and the sheet remaining lifetime $T2(i)$ can be accurately estimated.

As set forth hereinabove, according to an embodiment of the present invention, by calculating the remaining lifetime based on both the number of records by part and the operation amount by parts for at least a part of the various types of parts, the number of records by part and the operation amount by parts are reflected on the remaining lifetime. As a result, more accurate life estimation of the operation amount-dependent deteriorated parts can be achieved in comparison to a case that only the operation amount by parts is reflected on the remaining lifetime, or to a case that only the number of records by part is reflected on the remaining lifetime.

Although the invention has been described with respect to a specific embodiment for a complete and clear disclosure, the appended claims are not to be thus limited but are to be construed as embodying all modifications and alternative constructions that may occur to one skilled in the art that fairly fall within the basic teaching herein set forth.

What is claimed is:

1. A lifetime management device for an image forming apparatus that forms an image on a recording medium and includes a plurality of components, the lifetime management device comprising:

a counting unit that counts number of prints produced by the image forming apparatus with respect to each of the components;

a measuring unit that measures an operation amount of at least part of the components with respect to each of the components; and

a calculating unit that calculates a remaining lifetime of each of the components based on at least one of a lifetime index, the number of prints, and the operation amount,

wherein the calculating unit corrects the number of prints based on the operation amount to obtain a corrected value, and calculates the remaining lifetime based on the corrected value and the lifetime index, and

wherein the calculating unit calculates a first remaining lifetime based on the corrected value and the lifetime index, and a second remaining lifetime based on the operation amount and the lifetime index, and determines a shorter one of the first remaining lifetime and the second remaining lifetime as the remaining lifetime.

2. The lifetime management device according to claim 1, wherein, when a ratio of the operation amount to a value obtained by multiplying the number of prints by a predetermined coefficient is equal to or larger than a predetermined threshold, the calculating unit corrects the number of prints to be a corrected value larger than the number of prints for the part of the components.

3. The lifetime management device according to claim 2, wherein the calculating unit corrects the number of prints in a range having a predetermined upper limit.

31

4. The lifetime management device according to claim 1, wherein the calculating unit corrects the number of prints in a range having a predetermined upper limit.

5. The lifetime management device according to claim 1, wherein the calculating unit corrects the remaining lifetime, which has been obtained based on the number of prints and the lifetime index, based on the operation amount.

6. The lifetime management device according to claim 1, further comprising a determining unit that determines whether each of the components needs to be replaced based on the remaining lifetime.

7. The lifetime management device according to claim 1, wherein the calculating unit corrects any one of the number of prints and the remaining lifetime obtained based on the number of prints and the lifetime index only for part of the components whose deterioration depends more on the operation amount than on the number of prints.

8. An image forming system, comprising:

an image forming apparatus that forms an image on a recording medium and includes a plurality of components; and

a lifetime management device that manages lifetime information on each of the components of the image forming apparatus, the lifetime management device includes:

a counting unit that counts number of prints produced by the image forming apparatus with respect to each of the components;

a measuring unit that measures an operation amount of at least part of the components with respect to each of the components; and

a calculating unit that calculates a remaining lifetime of each of the components based on at least one of a lifetime index, the number of prints, and the operation amount,

wherein the calculating unit corrects the number of prints based on the operation amount to obtain a corrected value,

the calculating unit calculates a first remaining lifetime based on the corrected value and the lifetime index, the measuring unit measures as the operation amount an accumulated moving distance of at least one of the latent image carrier, the developing unit, the endlessly moving unit and the fixing unit, and

the calculating unit calculates a second remaining lifetime of at least one of the latent image carrier, the developing unit, the endlessly moving unit and the fixing unit based on the accumulated moving distance and the lifetime index, and determines a shorter one of the first remaining lifetime and the second remaining lifetime as the remaining lifetime.

9. The image forming system according to claim 8, wherein each of the components includes a storage unit that stores therein information on the number of prints and the operation amount.

10. The image forming system according to claim 8, wherein

the image forming apparatus includes

a latent image carrier that carries a latent image on an endlessly moving surface thereof;

a developing unit that develops the latent image on the latent image carrier to a visible image with a developer carried on the endlessly moving surface;

a transfer unit that transfers the visible image on the latent image carrier onto any one of an endlessly moving unit and a recording medium on a surface of the endlessly moving unit; and

32

a fixing unit that fixes the visible image on the recording medium, and

the calculating unit calculates a remaining lifetime of at least two of the latent image carrier, the developing unit, the endlessly moving unit, and the fixing unit.

11. The image forming system according to claim 8, wherein

the image forming apparatus further includes a cleaning unit that contacts the surface of the endlessly moving unit to clean the surface, and

the calculating unit calculates the second remaining lifetime of the cleaning unit based on the accumulated moving distance of the endlessly moving unit and the lifetime index.

12. The image forming system according to claim 11, wherein

the lifetime management device further includes a time counting unit that counts accumulated operating time of at least one of the latent image carrier, the developing unit, the endlessly moving unit, the fixing unit and the cleaning unit, and

the calculating unit calculates the second remaining lifetime of at least one of the latent image carrier, the developing unit, the endlessly moving unit, the fixing unit and the cleaning unit based on the accumulated moving distance and the accumulated operating time.

13. The image forming system according to claim 8, further comprising an information management apparatus connected via a communication line to the lifetime management device, wherein

the lifetime management device further includes:

a determining unit that determines whether each of the components needs to be replaced based on the remaining lifetime; and

an informing unit that informs the information management apparatus located at a remote place of a determination result obtained by the determining unit.

14. An image forming system, comprising:

an image forming apparatus that forms an image on a recording medium and includes a plurality of components; and

a lifetime management device that manages lifetime information on each of the components of the image forming apparatus, the lifetime management device includes:

a counting unit that counts number of prints produced by the image forming apparatus with respect to each of the components;

a measuring unit that measures an operation amount of at least part of the components with respect to each of the components; and

a calculating unit that calculates a remaining lifetime of each of the components based on at least one of a lifetime index, the number of prints, and the operation amount,

wherein when a ratio of the operation amount to a value obtained by multiplying the number of prints by a predetermined coefficient is equal to or larger than a predetermined threshold, the calculating unit corrects the number of prints to be a corrected value larger than the number of prints for the part of the components, the calculating unit calculates a first remaining lifetime based on the corrected value and the lifetime index, the measuring unit measures as the operation amount an accumulated moving distance of at least one of the latent image carrier, the developing unit, the endlessly moving unit and the fixing unit, and

33

the calculating unit calculates a second remaining lifetime of at least one of the latent image carrier, the developing unit, the endlessly moving unit and the fixing unit based on the accumulated moving distance and the lifetime index, and determines a shorter one of the first remaining lifetime and the second remaining lifetime as the remaining lifetime.

15. The image forming system according to claim 14, wherein

the image forming apparatus further includes a cleaning unit that contacts the surface of the endlessly moving unit to clean the surface, and the calculating unit calculates the second remaining lifetime of the cleaning unit based on the accumulated moving distance of the endlessly moving unit and the lifetime index.

16. The image forming system according to claim 15, wherein

the lifetime management device further includes a time counting unit that counts accumulated operating time of at least one of the latent image carrier, the developing unit, the endlessly moving unit, the fixing unit and the cleaning unit, and the calculating unit calculates the second remaining lifetime of at least one of the latent image carrier, the developing unit, the endlessly moving unit, the fixing unit and the cleaning unit based on the accumulated moving distance and the accumulated operating time.

17. The image forming system according to claim 14, wherein each of the components includes a storage unit that stores therein information on the number of prints and the operation amount.

34

18. The image forming system according to claim 14, wherein

the image forming apparatus includes a latent image carrier that carries a latent image on an endlessly moving surface thereof; a developing unit that develops the latent image on the latent image carrier to a visible image with a developer carried on the endlessly moving surface; a transfer unit that transfers the visible image on the latent image carrier onto any one of an endlessly moving unit and a recording medium on a surface of the endlessly moving unit; and a fixing unit that fixes the visible image on the recording medium, and

the calculating unit calculates a remaining lifetime of at least two of the latent image carrier, the developing unit, the endlessly moving unit, and the fixing unit.

19. The image forming system according to claim 14, further comprising an information management apparatus connected via a communication line to the lifetime management device, wherein

the lifetime management device further includes: a determining unit that determines whether each of the components needs to be replaced based on the remaining lifetime; and

an informing unit that informs the information management apparatus located at a remote place of a determination result obtained by the determining unit.
